Primary Examiner — Cynthia Ramirez(74) *Attorney, Agent, or Firm* — Gable Gotwals(57) **CLAIM**

The ornamental design for lift pocket for a refuse container, as shown and described.

DESCRIPTION

FIG. 1 is a front elevation view of a lift pocket for a refuse container.

FIG. 2 is a top plan view thereof, the bottom plan view being identical thereto.

FIG. 3 is a right side elevation view.

FIG. 4 is a left side elevation view.

FIG. 5 is a rear elevation view; and,

FIG. 6 is a perspective view showing the front, top, and right side.

The dash-dot-dot broken lines in the figures are to show environment and form no part of the claimed design.

1 Claim, 3 Drawing Sheets(56)
